SAFETY RAZOR

Samuel Ferich, Gary, Ind.

Application May 25, 1938, Serial No. 210,066

1 Claim. (Cl. 30—59)

The present invention relates to new and useful improvements in razors, particularly safety razors, and has for one of its important objects to provide, in a manner as hereinafter set forth, a device of this character embodying a novel construction and arrangement whereby the handle may be conveniently attached to the head at different angles to facilitate meeting various conditions when the razor is in use.

Another very important object of the invention is to provide a razor of the aforementioned character embodying novel means for clamping the blade in position.

Other objects of the invention are to provide a

razor of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of references designate corresponding parts through the several views, and wherein

Figure 1 is a view in rear elevation of an embodiment of the invention.

Figure 2 is a view in front elevation thereof.

Figure 3 is a front elevational view, showing the device open.

Figure 4 is a vertical sectional view, taken substantially on the line 4—4 of Fig. 2.

Figure 5 is a view in horizontal section, taken substantially on the line 5—5 of Fig. 3 but showing the handle in another position.

Figure 6 is a detail view in elevation of the clamp securing means, showing the elements separated.

Figure 7 is a detail view in section, showing one of the pivotal connections of the hinged clamp.

Figure 8 is a detail view in elevation of one of the clamp pivot pins.

Referring now to the drawings in detail, it will be seen that the embodiment of the invention which has been illustrated comprises a guard 1 of suitable metal. The guard 1 is provided with integral teeth 2 on its upper and lower edges. Rigidly secured on the back of the guard 1 is a substantially U-shaped bracket or yoke 3 of suitable metal. The substantially U-shaped bracket 3 is provided with threaded openings 4 in its side and rear or bight portions. The reference numeral 5 designates a detachable knurled handle

which is adapted to be threaded selectively into the openings 4 for mounting said handle on the head of the razor at different angles relative thereto, as suggested in full and broken lines in Fig. 5 of the drawings. The handle 5 is of substantially the shape shown to advantage in Figs. 1 and 2 of the drawings.

The reference numeral 6 designates a clamping plate of suitable metal which is hingedly mounted on the outermost lower teeth 2 of the guard 1. It may be well to here state that the clamp 6 is adapted to secure a conventional double edge flexible blade 7 in position against the front of the guard 1. Integral lugs 8 are provided on the corner portions of the clamp 6, said lugs being engageable in the usual corner notches or recesses in the blade 7.

The clamp 6 has formed therein a threaded opening 9 which is aligned with the usual central opening 10 in the blade 7 when said blade is mounted in position. As shown to advantage in Fig. 2 of the drawings, the arcuate outer face of the clamp 6 is knurled. Pivot screws 11 (see Figs. 7 and 8) are threadedly mounted in a pair of the lugs 8 of the clamp 6. The pivot screws 11 include reduced, smooth end portions or pins 12 which are journaled in the outermost teeth of one of the rows of guard teeth 2 for mounting the clamp 6 thereon for swinging movement.

The guard 1 has formed therein a substantially conical opening 13. The opening 13 is for the passage of a screw 14 which includes an operating head 15 on one end. Threaded on the screw 14 is a substantially conical nut 16 which is screwed up against the head 15 and which is received by the conical opening 13. The nut 16 is smaller than the opening 13 and in this manner the screw 14 is loosely retained in said opening. The screw 14 is adapted to be passed through the opening 10 in the blade 7 and threaded into the opening 9 in the clamp 6.

It is thought that the operation of the razor will be readily apparent from a consideration of the foregoing. To insert a blade, the screw 14 is unscrewed from the clamp 6 thereby permitting said clamp to be swung to open position. The blade 7 is then positioned on the clamp 6, as seen in Fig. 3 of the drawings, after which said clamp, with the blade thereon, is swung to closed position. Thus, the blade is brought between the guard 1 and the clamp 6. The screw 14 is then passed through the opening 10 in the blade 7 and threaded into the opening 9 of the clamp 6 for tightening said clamp on the blade. The loose mounting of the screw 14 in the conical opening 55

13 greatly facilitates threading said screw into the opening 9 as the clamp 6, of course, travels in an arc. The razor is now ready for use. By mounting the handle 5 on the head assembly in the positions suggested in Fig. 5 of the drawings either edge of the blade may be conveniently used while holding the razor in either the right or the left hand. This choice in the mounting of the handle on the head assembly of the razor also facilitates meeting other conditions that may be encountered when shaving. Further, it will be observed that the handle is rigidly secured to the head assembly in any of its free positions.

It is believed that the many advantages of a safety razor constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

A safety razor comprising a guard including

teeth, a handle mounted on said guard, a clamp for securing a blade in position against the guard, said clamp including integral lugs on its corner portions for retaining the blade in position relative to said clamp, pivot screws threadedly mounted in certain of the lugs and including unthreaded portions journaled in certain of the guard teeth for hingedly mounting the clamp on said guard, and means for releasably securing the guard in closed position, the guard having a substantially conical opening therein, the clamp having a threaded opening therein for alignment with the conical opening, said means including a thumb screw extending through the conical opening for engagement in the threaded opening, said thumb screw including a head engageable with the back of the guard, and a substantially conical nut threaded on the thumb screw and engaged with the head thereof, the conical opening accommodating said nut, the nut being smaller than the conical opening and constituting means for loosely securing the thumb screw on the guard.

SAMUEL ERICH.
